UNITED STATES PATENT OFFICE

155,776

DESIGN FOR A VEHICLE NUMBER PLATE ORNAMENT

Wilfred H. Burns, Melrose, Mass., assignor of one-half to Ivan H. Gile, Salem, N. H.

Application November 26, 1947, Serial No. 142,816

Term of patent 3½ years

(Cl. D14—6)

To all whom it may concern:

Be it known that I, Wilfred H. Burns, a citizen of the United States, residing at Melrose, in the county of Middlesex and State of Massachusetts, have invented a new, original, and ornamental Design for a Vehicle Number Plate Ornament, of which the following is a specification, reference being had to the accompanying drawing, forming part thereof.

Figure 1 is a front elevational view of a vehicle number plate ornament, showing my new design.
Figure 2 is a top plan view thereof, and
Figure 3 is an end view.

I claim:

The ornamental design for a vehicle number plate ornament, as shown.

WILFRED H. BURNS.
